UNITED STATES PATENT OFFICE

DONALD F. SPROUL, OF CHICAGO, ILLINOIS, ASSIGNOR TO CARDWELL WESTINGHOUSE COMPANY, A CORPORATION OF DELAWARE

CUSHIONING DEVICE

Application filed May 22, 1931. Serial No. 539,220.

The invention is herein disclosed as being for use as a bolster car support, though it may be applied in other situations.

The objects of the invention are to secure 5 simplicity of construction and action, as shown in the accompanying drawings illustrating the invention.

Fig. 1 is a central longitudinal section of the device;

10 Fig. 2 is a similar view, fragmentarily showing the device under compression;

Fig. 3 is an end view;

15 Fig. 4 is a sectional view on the line 4—4 of Fig. 1; and

Fig. 5 is a group of the various elements 20 of the device, except the springs, shown in perspective.

The device comprises a pair of alined cylinders 10, 11, each having at its remoter end 25 an outstanding flange 12, 13. Enclosed within the cylinders, and extending into both of them, are a plurality of friction shoes 14, 15, segmental in form and bearing against the inner surface of the cylinders. Each of 30 these shoes is provided with an outstanding flange 16, 17 intermediate of its ends and projecting between the two cylinders. Interposed between the shoe flanges and the flange of each of the cylinders is a helical spring 35 18, 19, which act as a unit and might be constructed as such except for the fact that the shoe flanges may be more conveniently interlocked with the spring elements when the latter is made in two sections.

40 Interfitting between the friction shoes are a pair of wedge-blocks 20, 21, their wedging faces cooperating with complementary faces, as 22, formed on the shoes adjacent to their ends. An expansible helical spring 23 acts between the two wedge-blocks to urge, by its inherent strength, the shoes against the cylinder walls.

The outer ends of the cylinders are open 45 and conveniently fit over retaining bosses formed on parts between which the device is interposed.

In service force applied to the two ends of the device move the cylinders relatively toward each other against the resistance of the 50 spring means 18, 19. The shoes 14, 15, being

interlocked with the spring means, are carried downwardly into cylinder 10, while the cylinder 11 advances more rapidly than the shoes, the parts being ultimately carried to the positions shown in Fig. 2, if the force 55 applied is sufficient to fully compress the spring. The friction developed between the shoes and cylinders, therefore, is constant, and its degree is determined by the strength 60 of the spring 23.

As the parts become worn they are held in intimate contact by the lengthening of the spring 23.

While but one pair of shoes is shown, obviously the use of a plurality of pairs would 65 be within the scope of the invention.

I claim as my invention:—

1. In a cushioning device, in combination, 70 a pair of alined cylinders each having an outstanding flange, spring means reacting between the flanges, a pair of segmental shoes each engaging the inner faces of both cylinders, inwardly facing spreading wedges carried by the shoes adjacent to their ends, wedge blocks cooperating with each pair of the 75 named wedges, a spring reacting between the wedge blocks, and means for interlocking the shoes with the spring means.

2. In a cushioning device, in combination, 80 a pair of alined cylinders each having an outstanding flange, spring means reacting between the flanges, a pair of segmental shoes each engaging the inner faces of both cylinders and having a lateral flange projecting between the cylinders and engaging the 85 spring means, inwardly facing spreading wedges carried by the shoes adjacent to their ends, wedge blocks cooperating with each pair of the named wedges, and a spring reacting between the wedge blocks. 90

3. In a cushioning device, in combination, 95 a pair of alined cylinders having outstanding flanges at their outer ends, a pair of segmental shoes extending into each cylinder and frictionally engaging the wall thereof and each having an outstanding flange projecting between the two cylinders, a spring reacting between said flanges and the flange of each cylinder, and means urging the shoes against the cylinder walls with constant pressure. 100

4. In a cushioning device, in combination, a pair of aligned cylinders having outstanding flanges, spring means reacting between the flanges, friction plates each engaging the inner faces of the cylinders and being interlocked with the spring means, and means for holding the shoes in engagement with the cylinder walls with constant pressure.

In testimony whereof I affix my signature.

DONALD F. SPROUL.
